Inventor,

Ralph C. Nash,

by himself, Gregory Antis.

UNITED STATES PATENT OFFICE.

RALPH C. NASH, OF NORTH PEMBROKE, MASSACHUSETTS.

LASTING-JACK.

SPECIFICATION forming part of Letters Patent No. 448,299, dated March 17, 1891.

Application filed November 11, 1890. Serial No. 371,027. (No model.)

To all whom it may concern:

Be it known that I, RALPH C. NASH, of North Pembroke, county of Plymouth, State of Massachusetts, have invented an Improvement in Jacks for Lasting Shoes, of which the following description, in connection with the accompanying drawings, is a specification, like letters and figures on the drawings representing like parts.

10 In the manufacture of boots and shoes the last containing the shoe is mounted on a jack, where it is held firmly while the shoe is being acted upon.

The object of this invention is to improve 15 the jack so that it may readily be adjusted vertically to the height desired for the operator, and also so that the jack may be tipped when desired, and I have also combined with the jack a swing-seat, and this seat is made 20 adjustable vertically.

Figure 1 in side elevation represents a jack embodying my invention, and Fig. 2 a section in the line *x*.

The column of the jack is composed of two 25 parts *A A'*, adjustably connected by bolts *A²*, in order that when the base of the standard rests on the floor the upper end of the part *A'* may be made to bear against the usual bench *B*, the standard by reason of its adjustment 30 being adapted to a bench of any usual height. The shank *B'* of the jack is slotted at *B³* for the reception of the clamping-screw *B³*, by which to hold the shank in any desired position vertically, according to the height of the 35 operator. This shank has pivoted on it at *a* a rocking head *b*, notched at its lower end, as at *2*, to be engaged by a locking device, shown as a bolt *3* and a spring *4* to actuate it, the 40 said bolt sliding in bearings *5*. The lower end of the locking device is connected by cord or link *b'* with a lever *B²*, so that by pulling the boot on the lever the locking device may be tipped about the pivot *a*. The 45 upper end of the head is slotted and properly shaped to receive upon or in it the heel-pin carriage *c*, and the toe-rest carriage *d*. The heel-pin *c'* rises from a block *c²*, pivoted at *c³* on the carriage *c*, an extension *c⁴* of the block having jointed to it a rod *c⁵*, which is 50 extended down through the head and surrounded by a spiral spring *c⁶*, a nut *c⁷* being applied to the lower end of the said rod to act

against one end of the said spring, the latter normally acting to keep the block and heel-pin in position. (Shown by full lines, Fig. 1.) 55

The toe-rest carriage has a toe-rest *d'* adjustably attached to it by a screw *d²*.

To apply a last (shown by dotted lines) to the jack, the heel-pin will be pulled back by hand into the position shown by dotted lines, 60 and the last having been put on the heel-pin the toe of the last will be laid on the toe-rest, as represented by dotted lines, the spring *c⁶* keeping it seated on the toe-rest. The base of the column has two ears *e e* to receive a 65 pin *e'*, which pivots to the column the arm *e²*, which supports the rod *e³* of the seat *e⁴*, the said rod having a sliding fit in a hub at the end of the arm *e²*, the hub having a set-screw *e⁵* by which to secure the seat in adjusted position. 70

To enable the arm *e²* to sustain a greater weight, I have connected to it a leg *f*, the lower end of which enters a bearing *f'* on the base of the column, and the leg turns therein 75 as the seat is swung on the pivot *e'*.

I claim—

1. In a lasting-jack, a column made in two parts sliding longitudinally one upon the other and adjustably connected together, 80 combined with the shank *B'*, adjustably connected to each of said parts, a head, and a jack mounted on the said shank, substantially as described.

2. In a lasting-jack column, the shank adjustably attached thereto, the head pivoted on the shank and notched at its lower end, and a locking device to co-operate with said notches and lock the head, combined with a heel-pin and toe-rest, to operate substantially 90 as described.

3. The jack-column and the jack having a shank adjustable on the said standard, combined with a connected pivoted seat and with means to adjust the seat vertically, substantially as described. 95

In testimony whereof I have signed my name to this specification in the presence of two subscribing witnesses.

RALPH C. NASH.
